INDEXING APPARATUS

George W. Crise, Mount Vernon, Ohio

Application June 2, 1939, Serial No. 277,115

7 Claims. (Cl. 172—239)

This invention relates to an indexing method and apparatus by which a movable member can be indexed or set at any desired one of a number of possible positions or settings. My indexing method and apparatus are particularly well suited for adaptation to radio tuning and for that reason are herein disclosed as being used for that purpose, but it should be understood that they are also adaptable to various other kinds of apparatus and uses.

With particular reference to the need for a satisfactory indexing method and apparatus in the field of radio tuning, it might be pointed out that heretofore it has been necessary to provide indexing devices for radio tuning with two commutator segments mounted with sufficient separation such that a position-selecting brush or contact riding thereon could rest upon an insulated section between the segments to obtain a stationary position. In these devices the commutator is driven by a motor to bring the insulated section under the brush or contact to thereby select the desired position or setting and the circuits are such that a tendency to cause such rotation occurs whenever the brush touches either segment. A certain tolerance has been necessary in devices of this kind to insure the driving motor being disconnected from both segments when the commutator arrives at the desired setting and this tolerance must be great enough to accommodate and isolate the largest brush or contact of a group containing a number of such position-selecting brushes or contacts. Because of this required tolerance more or less variation occurs in the tuning operation and this disadvantage has made it necessary for radio manufacturers to more or less standardize on the use of automatic frequency control to compensate for this variation. The use of automatic frequency control is undesirable because it increases cost and service problems and also causes a tendency for the radio to shift from one station to another if fading occurs in the signals or program being received.

Another disadvantage encountered in indexing devices as heretofore applied to radio tuning is that the segments of the commutator and position-selecting contacts have been required to carry the entire current for the driving motor and the frequent making and breaking of the circuits caused the contacts and commutator segments to become burned and worn with the result that the above mentioned tolerance was further increased with a corresponding increase

in the variation occurring in the indexing function.

My indexing method and apparatus overcome these disadvantageous and provide for accurate indexing and precision radio tuning without the need of automatic frequency control. It may, therefore, be said to be an object of my invention to provide a novel indexing method and apparatus for radio tuning and other purposes

5 by which a commutator or other member to be indexed or set can be accurately stopped and held at the desired position.

Another object of my invention is to provide a novel method and apparatus for indexing a movable member having spaced contact elements or segments, in which the rotative forces of an electric power device are unbalanced for moving said member toward a desired setting whereupon a position-selecting contact or brush connects such contact elements to cause balancing of the rotative forces of the power device for stopping the movable member at the desired setting.

Still another object of my invention is to provide a novel indexing method and apparatus, as just referred to, in which the electric power device is a shaded-pole type of motor and the engagement of the position-selecting contact or brush with the contact elements or segments of the movable member controls the circuits for the shading coils for determining the direction of rotation and the stopping of said movable member.

35 Other objects and advantages of my invention will be apparent from the following description when taken in conjunction with the accompanying sheets of drawings in which

40 Fig. 1 is a diagrammatic view showing indexing apparatus arranged according to my invention and with which my indexing method can be carried out;

45 Fig. 2 is a partial edge view of a part of the apparatus looking in the direction indicated by the line 2—2 of Fig. 1;

Fig. 3 is a partial perspective view of the manually operable switch device of my indexing apparatus;

50 Fig. 4 is a diagrammatic view showing a modified arrangement of indexing apparatus embodying my invention;

Fig. 5 is another diagrammatic view showing indexing apparatus embodying my invention;

55 Fig. 6 is another diagrammatic view showing another form of novel indexing means;

Fig. 7 is a partial elevational view of a rotatable commutator of an indexing apparatus; and

Fig. 8 is a partial transverse sectional view thereof taken on line 8—8 of Fig. 7.

More detailed reference will now be made to the accompanying drawings for the purpose of describing my novel indexing method and apparatus. Before proceeding with the detailed description it should be understood, however, that my invention may be embodied in various other forms of indexing apparatus and steps of procedure than those herein specifically disclosed.

In Fig. 1 of the drawings I show indexing apparatus with which my indexing method may be carried out and which may be applied to radio tuning or to various other uses where an oscillatable member is required to be indexed or set at any desired one of a number of available different positions. The apparatus here shown comprises a rotary contact device 10, an electric power device or motor 11 having a drive connection with the rotary contact device, and a manually operable switch device 12 for controlling the indexing operation.

The rotary contact device 10 may comprise a suitable frame 14 having spaced walls 15 in which a shaft 16 is journaled and a rotatable or oscillatable commutator or selector member 17 which is connected with the shaft for rotation in the frame. The shaft 16 may be an extension of the actuating shaft of the movable section of the main tuning condenser of a radio receiving set or may be a shaft having a suitable drive connection with such condenser shaft. The commutator 17 may comprise a disk 18 formed of electrically insulating material and a pair of segment-shaped contact elements 19 and 20 which are mounted on such disk with spaces or gaps 21 and 22 between their adjacent edges. The insulating disk 18 may have a groove in its outer edge in which a driving belt 23 engages for imparting rotation or oscillation to the commutator 17, although the commutator may be driven from the motor 11 in any suitable manner.

For cooperation with the commutator 17, I provide a plurality of position-selecting contacts or brushes 24 which may be mounted on one of the walls 15 of the frame. As many of these contacts may be provided as can be accommodated on the wall 15 or as may be desired, one such contact being provided for each station or position to which the commutator may be moved or set.

The contacts 24 may each comprise a resilient finger 24a of bronze or other conducting material and a contact element 24b which rides on the contact segments 19 and 20 of the commutator. The contact element 24b has its end rounded to spherical or other convex shape, as shown in Fig. 2, such that it will electrically connect the segments 19 and 20 of the commutator only when the latter is at a given position or setting. The finger 24a may be mounted on the wall 15 so as to be insulated therefrom and so that each finger is carried by, or connected with, a rotatable knob 24c. By rotation of these knobs the various contacts or brushes 24 can be manually set at positions corresponding with the various stations to which the commutator 17 may be moved.

For reasons hereinafter explained, the motor 11 which drives the commutator 17 is preferably an induction motor of the shaded-pole type whose rotation can be controlled by variation of the shading effect. This motor may have a lami-

nated frame 25 and an armature 26 operable therein. The armature may also be of laminated construction and has short-circuited inductor bars 26a. The frame 25 is constructed with two poles thereon each of which carries or is divided into two pole pieces, thereby providing the motor with two pairs of opposed pole pieces or sections. One such pair consists of pole sections 27 and 28 and the other pair consists of pole sections 29 and 30. The frame may also be constructed with arm portions 31 and 32 which connect the pole sections with a common leg 33.

The windings of the motor 11 consist of a primary winding 34 on the leg 33 and pairs of shading coils mounted on the respective pairs of opposed pole sections. The primary winding 34 has its ends connected respectively with current supply conductors 35 and 36 whereby this winding can be continuously energized by closing the switch 37 wherever the indexing device is to be put into operation. The shading coils of the pairs of opposed pole sections consist of coils 39 and 40 mounted respectively on the opposed pole sections 27 and 28 and coils 41 and 42 mounted respectively on the opposed pole sections 29 and 30. The shading coils 39 and 40 are connected in series with each other and likewise the coils 41 and 42 are also connected in series with each other, but in a separate circuit from that of the coils 39 and 40.

The characteristics of this shaded pole motor are such that if the primary winding 34 is energized and one set of shading coils, for example the set of coils 39 and 40, is energized by being short-circuited, while the other set of shading coils is deenergized by being open-circuited, the armature 26 will rotate in a counterclockwise direction. On the other hand if the set of shading coils 41 and 42 is energized, as by short-circuiting thereof, while the coils 39 and 40 are open-circuited the armature 26 rotates in a clockwise direction. The sets of shading coils are so wound that the shading effect of one set is substantially equal to and opposes the shading effect of the other set whenever both sets are energized simultaneously.

For the purpose of establishing the desired circuits through the pairs of shading coils of the motor 11, as will be explained hereinafter, I connect the leads at one end of the shading coils as indicated by the junction point 45. At the other end of the shading coils, the leads 46 and 47 are brought outside the motor.

The switch device 12 by which the indexing apparatus is controlled comprises a single jack type switch 50 and a push button 51, the latter being one of a group or series consisting of a number of such push buttons. The number of such push buttons occurring in the group will depend upon the number of different settings or stations to which the apparatus is capable of being set or indexed. Usually the number of such push buttons in a given apparatus will correspond with the number of position-selecting contacts or brushes of the rotary contact device 10. For the sake of clarity I show, in Fig. 1, only the push button 51 which corresponds with the position-selecting contact or brush 24 of the rotary contact device.

The switch device 12 may, as here shown, include an insulating support 54 in which the stem 55 of the push button 51 is slidable. A spring 56 disposed around the stem 55 normally holds the push button 51 in its extended position with

the contact head 57 of the stem engaging the underside of the support 54. The jack switch 58 comprises a pair of normally closed contacts 58, 59 and a pair of normally open contacts 60, 61. The contacts 58 and 59 are carried respectively by a pair of spring fingers 62 and 63 and the contacts 60 and 61 are carried respectively by spring fingers 64 and 65. Both pairs of spring fingers are mounted between layers of an insulating block 66 which is connected to the insulating support 54 by suitable screws 67. The spring fingers 63 and 64 may have extensions 69 and 70 thereon which carry a pusher or thrust member 71 formed of insulating material. An insulating spacer 72 disposed between the extensions 69 and 70 always holds the fingers 63 and 64 and the contacts 59 and 60 thereof in spaced-apart relation.

At a point between the push button 51 and the jack switch 58 I provide a pivoted latch 73 which cooperates with the contact head 57 and also with the insulating thrust member 71. This latch may be of a length to extend beneath all of the push buttons of the above mentioned series. As shown in Figs. 1 and 3, the latch 73 may have a rounded enlargement 74 pivotally retained in a socket of the support 54 and may also have a substantially hook-shaped arm portion 75 extending from such enlargement. A compression spring 75a acts on the latch 73 to normally hold the same in the path of downward movement of the contact head 57 of the push button 51. When the push button 51 is depressed, the contact head 57 engages the inclined section 76 of the latch and travels along the same until it passes the corner or shoulder point 77 whereupon it enters the hook portion of the arm and remains therein to hold the push button in its depressed position. While traveling along the inclined section 76 the contact head 57 exerts lateral pressure on the latch causing the same to swing about the axis of the rounded portion 74 thereby depressing the thrust member 71 and deflecting the spring fingers 63 and 64 downwardly. This downward deflection of the spring fingers 63 and 64 causes opening of the contacts 58 and 59, followed by a closing of the contacts 60 and 61. When the contact head 57 passes the shoulder point 77 the latch 73 swings back toward the right permitting contacts 58 and 59 to be reclosed and contacts 60 and 61 to be reopened.

The push button 51, or any other individual push button of the series which has been depressed, can be reset by manually lifting the same to disengage the contact head 57 from the hook portion of the arm. Such manual lifting is usually unnecessary, however, because the depressing of any button of the series will swing the latch 73 and this will release the button previously depressed. If one of the buttons should stick in its depressed position, as might result from its head 57 being oversize or misaligned, such button can be released by depressing any other button of the series far enough to cause its head to engage and swing the latch 73 further to the left.

To explain the controlling action produced by the actuation of the push button 51, various circuit connections must first be pointed out. As will be seen from the diagrammatic view of Fig. 1, one end of the pairs of shading coils 39, 40 and 41, 42 is connected with a terminal screw 79 of the switch device 12 by a conductor 80. A flexible lead 81 connects the terminal screw 79 with the pivoted latch 73. The spring finger 64

is also connected to the terminal screw 79 by a conductor 82. The other end of the set of shading coils 41 and 42 is connected with the spring finger 62 by the lead 46. The push button 51 is connected with its position-selecting contact or brush 83 by means of conductor 84. The segments 19 and 20 of the commutator 17 are connected respectively with the spring fingers 65 and 63, the segment 19 being connected with finger 66 through conductor 85 and flexible conductor 86 and the segment 20 being connected with finger 63 through flexible conductor 87. The other end of the set of shading coils 39 and 40 is also connected with the finger 65 through lead 47 and conductor 88. From the circuit connections just referred to, it will be seen that one end of the set of shading coils 39 and 40 is permanently connected with the segment 19 of the commutator through lead 47 and flexible conductor 86, and that the corresponding end of the set of shading coils 41 and 42 is connected with the segment 20 of the commutator through lead 48, normally closed switch contacts 58 and 59 and through flexible conductor 87.

Let it be assumed that the present position of the commutator 17 is a setting to which this member has been previously indexed by the depressing of a push button (not shown) corresponding with the position-selecting contact or brush 89. For this setting of the commutator it will be noted that the contact 89 bridges the gap 21 and electrically connects segments 19 and 20 with each other. At this time the two sets of shading coils are contained in energizing circuits which are parallel to each other and the energizing of the two sets of shading coils through these parallel circuits causes a substantial balancing of the rotative forces of the motor 11 with the result that the commutator 17 is held stationary.

Let it be assumed also that it is desirable to index the commutator to bring the gap 21 under the position-selecting contact 52, or in other words, to a setting corresponding with the position of this position-selecting contact. To do this the operator depresses the push button 51 which corresponds with the position-selecting contact 52. As explained above, the depressing of the button 51 causes swinging of the latch 73 and this, in turn, causes contacts 58 and 59 to be opened and contacts 60 and 61 to be closed. The separating of contacts 58 and 59 opens the circuit for shading coils 41 and 42 and the closing of contacts 60 and 61 causes short-circuiting of shading coils 39 and 40. This produces an unbalanced shading effect which causes an initial rotation of the armature 26 and the commutator 17 in a counterclockwise direction. This initial counterclockwise rotation of the armature causes the gap 21 to move out from under the previously chosen position-selecting contact 89 to produce what may be conveniently referred to as "unlocking." The result of this initial counterclockwise rotation of the armature or "unlocking" is to cause the previously chosen contact 89 to ride only on segment 20 and to thereby break the electrical connection between the segments.

The movement of the contact head 57 of the push button 51 past the shoulder point 77 and into the hooked portion of the latch 73 permits the contacts 58 and 59 to reclose and the contacts 60 and 61 to be reopened, as explained above. The reopening of the contacts 60 and 61 causes deenergization of shading coils 39 and 40 and the reclosing of contacts 58 and 59 causes closing

of an energizing circuit for the shading coils 41 and 42. This energizing circuit may be traced from junction point 45 through conductor 80, flexible conductor 81, to latch 73, through push button 51 and flexible conductor 84 to segment 20, then through flexible conductor 81, jack switch contacts 59 and 58, and then through lead 46 and shading coils 42 and 41, back to junction point 45.

The energizing of shading coils 41 and 42 while shading coils 39 and 40 are deenergized results in an unbalanced condition for the rotative forces of the motor 11 causing clockwise rotation of the commutator 17. During this clockwise rotation, the gap 21 passes under position-selecting contact 89 and other similar contacts 24 and at each such point the segments of the commutator are electrically connected with each other to cause momentary energization of both sets of shading coils in parallel with each other. Although the energization of both sets of shading coils at these points tends to slow down the rotation of the armature, the effect is only momentary and the momentum of the armature causes the gap to glide past the contacts. However, when the gap 21 reaches the position-selecting contact 52, the element 24b of this contact bridges the gap and for an interval of time, electrically connects the segments 19 and 20. During this interval the previously deenergized shading coils 39 and 40 will be energized in parallel circuit with the shading coils 41 and 42 and the tendency will be for the motor to come to a stop as the result of the friction of the moving parts.

The momentum of the commutator 17 may be sufficient to carry the gap 21 beyond the position-selecting contact 52, and this will result in this contact being shifted from the segment 20 on to the segment 19. This will cause opening of the energizing circuit for shading coils 41 and 42 and a closing of the energizing circuit for shading coils 39 and 40. The result will be an unbalancing of the rotative force of the motor 11 tending to cause rotation of the commutator in a counter-clockwise direction. This rotation of the commutator will bring the gap 21 back under the position-selecting contact 52. Such over-running of the gap 21 beyond the position-selecting contact 52 alternately in opposite directions, produces an oscillation of the commutator which will decrease in amplitude by reason of the friction on the moving parts. The commutator presently comes to rest with the gap 21 beneath the position-selecting contact 52 and is held in this position as long as the push button switch 51 remains depressed. The stopping of the commutator in this manner, with the gap under the desired position-selecting contact, may be conveniently referred to as "locking-in."

If it should be desirable to index the commutator to a different setting, the operator first releases the push button 51 and then depresses the push button corresponding with whatever different setting he desires for the commutator. The operation above explained is repeated with the commutator first rotating in a counterclockwise direction to "unlock" the gap 21 from the previously chosen contact 52, after which the rotation of the commutator reverses or continues, as the case may be, to bring the gap under the newly chosen position-selecting contact.

If the operator desires to change the setting for one of the position-selecting contacts, for example, the contact 52, he presses the corresponding push button to cause the commutator to be

shifted to bring the gap 21 under the chosen contact. He then grasps the knob 24c which is frictionally mounted in the frame wall 15 and rotates the knob to shift the contact in the desired direction. During this shifting of the contact the gap 21 will follow the contact to any position within the range to which the finger 24a can be swung. In this way the position-selecting contacts can be initially set, or subsequently reset, at positions corresponding with the desired stations or frequencies. The position-selecting contacts will remain at these settings until a future manual change is made.

In Fig. 4 of the drawings I have shown another arrangement of indexing apparatus which can be used for precision radio tuning or for various other purposes. This indexing apparatus comprises a rotary contact device 91, a driving motor 92 and a manually operable switch device 93 for controlling the indexing operation.

The rotary contact device 91 may be similar in construction to the device 10 of Fig. 1, that is to say, it may include a commutator 94 comprising an insulating disk 95 having a pair of segment-shaped contacts 96 and 97 mounted thereon with their adjacent ends spaced apart by gaps 98 and 99. The commutator 94 may be connected to and carried by a shaft 100 which is journaled in a suitable frame 101 and may be connected with the actuating shaft of a main tuning condenser of a radio set. The insulating disk 95 may have a peripheral groove in which a driving belt or strand 102 engages.

This rotary contact device 91 also includes a plurality of position-selecting contacts 103 corresponding in number with the number of stations to which the commutator may be indexed or set. In this instance I show only position-selecting contacts 103 and 104, but several may be provided. These contacts may be similar to the contacts 24 of Fig. 1, that is to say, they may be frictionally mounted on the frame 101 and each may have a resilient conducting finger or arm and a round-nosed contact element 105 which rides on the segments 96 and 97.

The motor 92 may be a single-direction motor adapted to be driven by either alternating or direct current and arranged so that, when energized, it will rotate in a clockwise direction. The belt 102 may have one end thereof wrapped around the pulley 107 of the motor and anchored thereto as indicated at 108. The opposite end of the belt may extend beyond the commutator 94 and may have a weight 109 suspended thereon. This weight has a mass such that the force of gravity will rotate the commutator and the motor in a counterclockwise direction whenever the motor is deenergized. On the other hand, the mass of the weight 109 and the characteristics of the motor 92 are such, that when the motor is fully energized its power will be sufficient to rotate the commutator clockwise and to lift the weight against the action of gravity, and when the energization of the motor is reduced, as by inserting a resistance in the motor circuit, the power of the motor will be reduced sufficiently to merely balance the weight 109 whereby the commutator can be held in a desired position as long as such balanced condition obtains.

The switch device 93 may be of the push-button type having a plurality of pairs of push buttons. In this instance I show push buttons 111 and 112 constituting one of such pairs and which are connected with a switch lever 113 at

opposite sides of the pivot 114 thereof. The contacts associated with the push buttons 111 and 112 include contacts 115 and 116 which are connected respectively with position-selecting contacts 103 and 104 by conductors 117 and 118. These contacts also include three arcuately arranged stationary contacts 120, 121 and 122 and a movable contact 123 adapted to sweep across these arcuately arranged contacts. The contact 123 may be carried by the lever 113 but is insulated therefrom by the interposed body 125. Suitably located stops 126 and 127 may be provided so as to be engaged by the lever 113 when the latter is swung to one or the other of its positions by the depressing of the push buttons 111 or 112.

Current for operating the motor 92 may be supplied through line conductors 129 and 130 and through a switch 131 which is closed when the indexing apparatus is to be put into operation. The power conductor 129 is interrupted at a point 132 at which the switch formed by the cooperating contacts 120—123 is inserted. The contact 121 is connected with the outer section of the power conductor 129 and the contacts 120 and 122 are connected with the inner section 129a. The movable contact 123 is of a length such that it will bridge the pair of contacts 121 and 122 or the pair of contacts 120 and 121, depending upon the position of the lever 113, but will cause opening of the power circuit during the shifting of the lever from one of its extreme positions to the other. This interruption of the power circuit is desirable at the beginning of each indexing operation for de-energizing the motor 92 so that the commutator 94 can be rotated by the weight 109 in a counterclockwise direction to shift the gap 98 out from under the position-selecting contact to which the apparatus was previously indexed. This interruption of the power circuit and resulting counterclockwise rotation of the commutator may be referred to as an "unlocking" operation.

The commutator segments 96 and 97 are connected respectively with the power conductors, 45 the segment 98 being connected with the conductor section 129a through flexible conductor 134 and resistance 135 and the segment 97 being connected with the line conductor 130 through flexible conductor 136 and resistance 137. One of the terminals of the motor 92 is also connected with power conductor 138 by conductor 138 and the other motor terminal is connected with the switch lever 113 by conductor 139. The resistance 135 may or may not be 50 needed, depending upon the voltage of the power circuit. The motor 92 is so designed as to be fully or normally energized when operating with the normal voltage and current supply, and this may be with or without the resistance 135 in the motor circuit as conditions require.

From the circuit connections and switch arrangement just explained, it will be seen that by depressing either of the push buttons 111 or 112, an energizing circuit for the motor 92 can be established. When the push button 111 has been depressed, as shown in the drawing, the lever 113 is swung to a position in which it engages contact 115 and the contact 123 overlies and connects contacts 120 and 121. By move- 70 ment of the lever 113 to this position an energizing circuit for the motor has been completed which may be traced from power conductor 130 through conductor 138 to the motor and then back through conductor 139 to switch lever 113, 75

then from contact 115 through conductor 117 to position-selecting contact 103 and through segment 96 of the commutator 94, flexible conductor 134 and resistance 135 to power conductor 5 section 129a. From this point the motor circuit continues through contacts 120, 123 and 121 back to power conductor 129. The resistance 135 is of such value that when a motor energizing circuit has been established as just traced, the motor will run in a clockwise direction and will develop sufficient power to rotate the commutator in the same direction and lift the weight 109 against the action of gravity.

The rotation of the commutator 94 in a clockwise direction by the motor continues until the gap 98 comes under the contact 103 whereupon this contact electrically connects the segment 96 with the segment 97. When this occurs it will be seen that a circuit connection is established 20 between the rotary contact device 91 and the power conductor 130 which is in parallel with the motor 92. This parallel circuit connection may be traced from segment 96 through contact 103, which is then engaging in gap 98, to segment 97 and thence to power conductor 136 through flexible conductor 136 and resistance 137. The value of the resistance 137 is such that a current flow will take place through this parallel circuit of a value to reduce the energizing current flowing through the motor to a point where the power output of the motor is only sufficient to balance the gravity pull exerted by the weight 109. Because of this balanced condition, the commutator will come to a stop with the gap 98 under the contact 103 and will remain in this position as long as the button 111 remains depressed.

If the clockwise rotation of the commutator 94 should cause the gap 98 to travel beyond the contact 103, it will be seen that this contact will then disengage the segment 96 and will engage only the segment 97. This will result in the motor energizing circuit being broken at the commutator 94 and this will permit the weight 109 to rotate the commutator in a counterclockwise direction to return the gap 98 to a position beneath the contact 103 thereby reestablishing the motor energizing circuit and producing a "locking-in" effect, as explained above.

When the operator wishes to index the device to a different setting or station, for example, that with which the push button 112 corresponds, he depresses this button and thereby shifts the switch lever 113 to engagement with the contact 116. This same movement of the switch lever 113 shifts the contact 123 to the contact 122 and in so doing, interrupts the motor circuit so that the weight 109 can rotate the commutator in a counterclockwise direction and thereby "unlock" the gap 98 from its engagement with the contact 103 to which the apparatus was previously indexed. This counterclockwise rotation will continue until the segment 96 is engaged by the contact 104 whereupon the motor 92 will be energized through the circuit above traced to cause, either a balancing of the rotative forces if the contact 104 remains in engagement with both of the segments 95 and 97, or to produce a clockwise rotation of the commutator if the contact 104 overruns the gap 98 and engages only the segment 96. From the foregoing explanation it will be readily seen that the oscillation of the commutator 94 under the influence of the motor 92 and the weight 109 will result in the gap 98 being quickly brought to a stop beneath the

chosen position-selecting contact and will be held in this position until a different setting is desired.

In Fig. 5 of the drawings I show indexing apparatus similar to that of Fig. 4, but of more simplified form. In this apparatus I show a commutator 141 which may be mounted on the condenser shaft 142 and which may be one of a series of similar commutators mounted on such shaft. The commutator may comprise an insulating disk 143 having contact segments 144, 145 and 146 mounted on its periphery and also having a pulley 147 connected therewith or with the shaft 142. The segment 145 is spaced from the segment 144 and the segment 146 by gaps 148 and 149 and is a dead segment. The segment 146 is a relatively short segment which is separated from the segment 144 by a gap 150, but is connected with the latter segment through a resistance 151.

A single-direction motor 153 adapted to be operated by direct or alternating current is located adjacent the commutator and has a belt or strand 154 anchored to its pulley 155 and extended over the pulley 147 of the commutator. A weight 156 is suspended on the strand 154 of sufficient mass to balance the power output of the motor when it is operated at reduced energization or to turn the motor and commutator 141 in a counterclockwise direction when the motor is deenergized. Leads or conductors 157 and 158 extending from the motor are connected respectively with the power conductor 159 and the segment 144 of the commutator.

A brush or position-selecting contact 160 mounted in relatively fixed position cooperates with the commutator and rides on the segments thereof. This contact may comprise a holder 161 which is connected with power conductor 162 by a conductor 163 and a contact element 164 in the holder which is adapted to be pressed against the commutator segments by a spring 165.

When a push-button switch or other manually operable switch 165 corresponding with the position-selecting contact 160 is closed, an energizing circuit for the motor is established through conductors 157 and 158 and the commutator segment 144. The closing of this circuit causes the motor to drive the commutator in a clockwise direction, but when the segment 146 moves under the contact 160, the resistance 151 is inserted into the motor circuit. This reduces the energization of the motor to a point where its power output balances the pull exerted by the weight 156 whereupon a substantially balanced condition results and the commutator is held against further rotation in either direction.

If the momentum of the commutator should carry the segment 146 in a clockwise direction beyond the contact 160, the contact will pass onto the dead segment 145 and the motor will be completely deenergized. This will permit the weight 156 to promptly rotate the commutator in a counterclockwise direction to bring the segment 146 back under the contact 160 and thus produce a "locking-in" at the desired setting or station.

In the operation of the indexing apparatus of Fig. 5, some variation may occur in the setting or indexing of the commutator because of the segment 146 being longer than the width of the contact 160 and, for this reason, it may be desirable to employ automatic frequency control in conjunction with this indexing apparatus.

In Fig. 6 of the drawings I have shown a com-

mutator 166 and a position-selecting contact 167 which correspond with the commutator and position-selecting contact of the indexing apparatus of Fig. 5, but are constructed in a manner to secure certain important advantages. The commutator 166 has live and dead segments 168 and 169 and also has an intermediate segment or part corresponding with the segment 146 of Fig. 5. This latter segment or part comprises a screw 170 mounted in a substantially radial position on the insulating disk 171 of the commutator with its outer end extending into a gap 172 between the adjacent ends of the segments 168 and 169. A recess or opening 173 formed in the insulating disk 171 affords access to the screw 170 for adjustment thereof. This screw is connected with the live segment 168 through a flexible resistance element 174.

The position-selecting contact 167 has a rounded head 175 which rides the segments 168 and 169 of the commutator and engages the point or tip of the screw 170 when the commutator reaches the desired index position or setting. When the contact 167 engages the screw it disengages the segments 168 and 169 and results in the motor energizing circuit being established through the resistance 174 whereupon the commutator 166 is held at an accurately indexed setting. The use of the screw 170 as the intermediate segment permits the gap width to be reduced and also affords a means for readily making adjustments and taking up wear.

Instead of mounting a screw in the insulating disk of the commutator, as shown in Fig. 6, I may construct the insulating disk with a slot 177 therein and mount a contact member 178 on the disk with a radially extending rib 179 thereof disposed in such a slot, as shown in Figs. 7 and 8. The member 178 may be connected with the insulating disk by means of clamping and adjusting screws 180 and 181 and may have a flexible portion of reduced thickness 182 whereby the position of contact rib 179 in the slot 177 and relative to the faces of contact segments 183 and 184 can be varied. An advantage for this form of commutator segment or contact is that it extends radially of the commutator and permits a large number of position-selecting contacts to be arranged at desired points and all of which can operate on the same commutator.

From the foregoing description and the accompanying drawings, it will now be readily seen that I have provided a novel indexing method and apparatus whereby the tuning condenser of a radio apparatus, or other member to be indexed or set, can be moved to a desired position in response to actuation of a push-button control switch located either adjacent the apparatus or remote therefrom. It will be seen furthermore that in the use of my novel indexing method and apparatus the member to be indexed is first rotated by unbalancing the rotative forces of the power device and is then brought to a stop at the desired setting or index position by balancing the rotative forces of the power device. The indexing apparatus which I have provided is of such relatively simple form that it can be initially manufactured in an economical manner and will require much less attention and servicing than any prior indexing apparatus with which I am familiar and, when applied to radio tuning, will also eliminate the need for automatic frequency control.

Having thus described my invention, I claim:

1. In combination, a frame, a member rotatably supported by said frame and having a pair of spaced segments, an alternating current motor adapted to drive said member and having a pair of opposed shading coils connected respectively with said segments, and a selector contact riding said segments and having circuit connections with said shading coils for short-circuiting one coil while riding one segment and short-circuiting the other coil while riding the other segment and short-circuiting both coils when in engagement with both segments said selector contact comprising an arm having pivotal connection with said frame permitting manual swinging of the arm for adjustment of the contact to different settings.

2. In combination, a movable member having a pair of spaced segments, an alternating current motor adapted to drive said member and having a pair of opposed shading coils connected respectively with said segments, a selector contact riding said segments and having circuit connections with said shading coils for short-circuiting one coil while riding one segment and short-circuiting the other coil while riding the other segment and short-circuiting both coils when in engagement with both segments, and switch means included in said circuit connections and operable for short-circuiting one of the shading coils and opening the circuit of the other coil.

3. In apparatus of the character described, a rotatable member carrying a pair of adjacently spaced segments, an alternating current shaded-pole motor connected with said member to drive the same and having opposed shading coils, a position-selecting contact adapted to ride said segments, a switch having a plurality of pairs of contacts and actuating means therefor, and circuit connections for said shading coils including means connecting an end of one coil with one of said segments and means connecting an end of the other coil with the other of said segments through one pair of the switch contacts and means connecting the remaining ends of both coils with said position-selecting contact through another pair of the switch contacts.

4. In apparatus of the character described, a rotatable member carrying a pair of adjacently spaced segments, an alternating current shaded-pole motor connected with said member to drive the same and having opposed shading coils, a position-selecting contact adapted to ride said segments, switch means having pairs of cooperating contacts including at least one pair of normally closed contacts and one pair of normally open contacts and manually operable actuating means for causing closing of the open contacts followed by opening of the closed contacts and a reclosing of said closed contacts, and circuit connections for said shading coils including means connecting one coil with one of said segments and means connecting the other coil with the other segment through said pair of normally closed contacts and means connecting both coils with said position-selecting contact through said normally open contacts.

5. In apparatus of the character described, a frame, a member rotatably supported by said

frame and carrying a pair of adjacently spaced segments, an alternating current shaded-pole motor connected with said member to drive the same and having opposed shading coils, a plurality of position-selecting contacts adapted to ride said segments, switch means comprising a plurality of manually movable position-selecting contacts electrically connected respectively with the first mentioned position-selecting contacts and a contact common to said manually movable contacts and adapted to be individually engaged thereby, and circuit connections connecting an end of one of said coils with one of said segments and an end of the other coil with the other segment and the remaining ends of both coils with said common switch contact, said position-selecting contacts comprising arms mounted on said frame for individual swinging so as to permit manual adjustment of said contacts to different settings.

6. In apparatus of the character described, a rotatable member carrying a pair of adjacently spaced segments, an alternating current shaded-pole motor connected with said member to drive the same and having opposed shading coils, a plurality of position-selecting contacts adapted to ride said segments, switch means comprising a plurality of manually movable position-selecting contacts electrically connected respectively with the first mentioned position-selecting contacts and a contact common to said manually movable contacts and adapted to be individually engaged thereby, and circuit connections connecting an end of one of said coils with one of said segments and an end of the other coil with the other segment and the remaining ends of both coils with said common switch contact, said switch means also including a pair of normally closed contacts located in the circuit connections for one of said coils and adapted to be opened by actuation of one of said manually movable contacts.

7. In apparatus of the character described, a rotatable member carrying a pair of adjacently spaced segments, an alternating current shaded-pole motor connected with said member to drive the same and having opposed shading coils, a plurality of position-selecting contacts adapted to ride said segments, switch means comprising a plurality of manually movable position-selecting contacts electrically connected respectively with the first mentioned position-selecting contacts and a contact common to said manually movable contacts and adapted to be individually engaged thereby, circuit connections connecting an end of one of said coils with one of said segments and an end of the other coil with the other segment and the remaining ends of both coils with said common switch contact, said switch means also including a pair of normally closed contacts located in the circuit connections for one of said coils and adapted to be opened by actuation of one of said manually movable contacts and a pair of normally open contacts adapted to be closed by said one manually movable contact, and means connecting the contacts of said normally open pair with the ends of the other of said coils.

GEORGE W. CRISE.
